WILLIAM T. COGHLAN, OF MORRISTOWN, NEW JERSEY.

DESIGN FOR A SPOON.

SPECIFICATION forming part of Design No. 32,327, dated March 13, 1900:

Application filed February 6, 1900. Serial No. 4,288. Term of patent 7 years.

To all whom it may concern:

Be it known that I, WILLIAM T. COGHLAN, a citizen of the United States, residing at Morristown, in the county of Morris and State of New Jersey, have invented a new and original Design for a Spoon, of which the following is a specification, reference being had to the accompanying drawings, forming a part thereof.

10 In the said drawings, Figure 1 is a perspective view of a spoon embodying my design. Fig. 2 is an under side view of the same, and Fig. 3 is a cross-section taken at the line x^3 in Fig. 1. These several views are deemed necessary to illustrate my design.

15 The leading feature of my design consists in the spoon having at the side of the bowl an incurved indentation of the margin.

A is the concave bowl of the spoon, and B is the handle thereof.

20 a is the margin of the bowl A, and b is the incurved indentation in the margin a of the bowl, at one side of the latter. This incurved portion forming the indentation is nearly or quite upright.

25

What I claim is—

The design for a spoon, substantially as shown and described.

20 In witness whereof I have hereunto signed my name, this 24th day of January, 1900, in 30 the presence of two subscribing witnesses.

WILLIAM T. COGHLAN.
